UNITED STATES PATENT OFFICE.

HERBERT J. WILLMOTT, OF CAMBRIDGE, MASSACHUSETTS, ASSIGNOR TO PETER GRAY & SONS INC., OF CAMBRIDGE, MASSACHUSETTS, A CORPORATION OF MASSACHUSETTS.

COOLER FOR LIQUIDS.

Application filed May 31, 1922. Serial No. 564,989.

To all whom it may concern:

Be it known that I, HERBERT J. WILLMOTT, a citizen of the United States, residing in Cambridge, in the county of Middlesex and State of Massachusetts, have invented an Improvement in Coolers for Liquids, of which the following description, in connection with the accompanying drawings, is a specification, like characters on the drawings representing like parts.

This invention relates to a cooler for liquids and is herein shown as embodied in a cooler for drinking water, especially adapted for use in railway cars. The invention has for its object to provide a hygienic cooler of superior cooling capacity as will be described.

The invention further has for its object to provide a cooler in which the container for the drinking water is bodily movable into and out of the ice container with the water faucet attached thereto, and is supported by the ice container with which it co-operates to be retained therein against accidental displacement.

These and other features of this invention will be pointed out in the claims at the end of this specification.

Fig. 1 is a front elevation of a water cooler embodying this invention.

Fig. 2, a vertical section of the cooler shown in Fig. 1 on the line 2—2.

Fig. 3, a horizontal section on the line 3—3, Fig. 2, and

Fig. 4, a detail in section of the locking device shown in Fig. 1, to be referred to.

Referring to the drawings, *a* represents a container for the drinking water, and *b* a container for ice and ice water, which accumulates by the melting of the ice therein.

For convenience, the container *a* may be designated the water container and the container *b* the ice container.

Both containers may and preferably will be made of sheet metal.

The water container *a* is preferably made substantially rectangular in cross section and is provided as shown in Figs. 2 and 3 with a bottom wall 10, upright side walls 12, 13, a rear wall 14 and a front wall 15 soldered or otherwise secured together liquid tight.

The side and rear walls 12, 13, 14, of the water container *a*, are preferably inclined downward to form a downward tapering

water container. The container *a* is provided at its upper end with a supplemental front wall formed by a bent plate or strip 16, which is soldered to the front wall 15 and to the side walls 12, 13, which latter are cut away at their upper ends, so that the supplemental wall 16 forms with the front wall 15 a channel 17, which is open at its opposite ends.

The mouth of the water container *a* is normally closed by a removable cover 18.

The front wall 15 extends above the top of the container and also beyond the sides of the same for a purpose as will be described.

The water container *a* co-operates with the ice container *b*, which latter is substantially U-shaped in cross-section and is provided with a main compartment 20 and with side compartments 21, 22, extended forwardly therefrom (see Fig. 3).

The main compartment 20 is provided with a bottom wall 23 and with front and rear walls 24, 25, and the side compartments 21, 22 are provided with outer side walls 26, 27 and with inner side walls 28, 29. The side compartments 21, 22 are also provided with front walls 30, 31, which are herein shown (see Fig. 3), as integral with the inner side walls 28, 29, and soldered or otherwise connected liquid-tight with the outer side walls 26, 27.

The outer side walls 26, 27, may be integral with the rear wall 25, and the inner side walls 28, 29, may be integral with the front wall 24 of the main compartment 20.

The inner side walls 28, 29 and the front wall 24 may and preferably will be inclined downward to form in the ice container a tapering recess or well for the reception of the water container *a*, which tapering well is open at its top, bottom and front, and whose inclined walls 24, 28, 29 are engaged by the inclined walls 14, 12, 13, of the water container to support the latter and to obtain the maximum cooling effect of the cooling medium in the ice compartment upon the contents of the container *a*.

Provision is made for detachably securing the water container *a* to the ice container *b* against accidental displacement through the front of the recess or well therein.

To this end, the ice container *b* is provided at its front surface with hooks or bent lugs 33 (see Figs. 1 and 4), which co-operate with

slotted plates or castings 34 affixed to the front wall 15 of the water container *a*, so as to retain the water container in the well or recess in the ice container, until bodily removed therefrom by moving the water container in two directions substantially at right angles to each other.

In the present instance, four plates or castings 34 are employed, two being located 10 near the top, and two near the bottom of the front wall 15, and each plate or casting is provided with a vertical slot 35 and with a horizontal slot 36 extended from the lower end of said vertical slot.

15 The horizontal slot 36 is made longer than the horizontal portion 37 of the bent lug or hook 33, so that the horizontal portion 37 may pass through the horizontal slot 36 when the water container *a* is moved bodily 20 in a horizontal direction into the recess or well in the ice container, and thereby bring the horizontal portion 37 in front of the plates or casting, which enables the water container to then be moved vertically downward until its tapering rear and side walls 14, 12, 13, engage the tapering walls 24, 28, 29, of the ice container *b*, at which time the horizontal portions 37 of the hooks 33 engage a solid portion of the casting or plate 25 above the horizontal slot therein and thus securely lock the water container to the ice-container against accidental displacement, as represented in Fig. 1.

The water container *a* may be removed 30 from the ice container *b* by first moving the former upwardly until the horizontal slots 36 in the front wall are opposite the horizontal portion 37 of the hooks 33, after which the water container is moved outwardly substantially at right angles to the direction in which it is moved upwardly.

40 The front and bottom walls of the water container *a* may and preferably will be made as heat insulating walls, by providing said walls with outer members or plates 40, 41, which are spaced apart from the walls 15, 10, and between which is interposed a layer 42 of cork or other heat-insulating material. The ice-container *b* may be provided 45 with similar insulating side, back and bottom walls formed by outer members 43, 44, 45, and interposed layers 46 of heat-insulating material.

50 The water container *a* has connected with it the usual faucet 50, which may be attached to the front wall or as herein shown to the bottom wall thereof, and which is movable with the water container.

55 Provision is made for hanging the cooler upon a vertical partition or wall 51 of the railway car and to this end, the rear wall of the ice container has riveted to it a bar or strip 52, which is bent at its upper end to form a hook 53, which engages the lower 60 wall of a slot 54 in the partition 52. The

ice container *b* is provided with an overflow pipe 55, which has its lower end extended through the bottom walls 23, 45 and has its upper end extended to near the top of the ice container, where it is provided with a 70 hood 56 which is closed at its upper end and is secured by arms 57 to said overflow pipe.

The hood 56 forms a passage 58 outside of the upper end of the overflow pipe 55, and as the water from the melting ice accumulates 75 in the ice-container *b*, it rises in the passage 58 and overflows into the pipe 55, thereby creating a suction in the passage 58, which siphons the water down to the level of the lower edge of the hood, and thereby quickly 80 lowers the level of the water in the ice compartment to a level at which danger of the water being thrown upwardly over the water container by the swaying of the railway car when in use, is avoided or at least reduced to a minimum.

The front wall 24 of the compartment 20 may be supported at its upper end by a cross bar 60, which is soldered to the side walls 26, 27. 90

The ice container *b* may have secured to the bottom of its side walls, metal strips or bars 62 to rest on angle iron brackets 63 attached to suitable upright walls 64 in the car, said strips or bars having bent fingers 65 at their opposite ends which co-operate with the ends of the brackets 63 to prevent 95 excessive movement of the cooler on said brackets.

The overflow pipe 55 is preferably screw-threaded at its lower end to detachably connect it with a sleeve 70, which construction enables the overflow pipe to be unscrewed and removed from the top of the ice container, to completely drain the water from 105 the ice container when desired.

A preferred embodiment of the invention is herein shown, but it is not desired to limit the invention to the particular construction shown. 110

Claims:

1. In a cooler of the character described, in combination, an ice container having a main compartment and side compartments extended from said main compartment and forming between them a recess or well open at its front, a water container insertable into and removable from said recess or well through the open front thereof, and means on the ice compartment co-operating with the front wall of the water container for retaining the latter in said recess or well and for compelling the water container to be moved in directions substantially at right angles to each other in order to insert and remove it into and from said recess or well. 115

2. In a cooler of the character described, in combination, an ice container having a main compartment and side compartments extended from said main compartment and 120

forming between them a recess or well open at its front, a water container insertable into and removable from said recess or well through the open front thereof, and having

5 a front wall provided with angle slots, and hooks attached to the ice container co-operating with said slots in one position of the water container to permit the latter to be inserted into and removed from said 10 recess or well and co-operating with a solid portion of the front wall in another position of the water container to retain the latter in said recess or well.

3. In a cooler of the character described, 15 in combination, an ice container having a main compartment and side compartments extended from said main compartment and forming between them a downward tapering recess or well open at its front, a water 20 container insertable into and removable from said recess or well through the open front thereof and having downward tapering walls to engage and be supported by the walls of said tapering recess or well, and 25 means for retaining the water container in said recess or well.

4. In a cooler of the character described, 30 in combination, an ice container provided with a recess or well open at its front, a water container insertable into and removable from said recess or well through the open front thereof and having its front wall

forming the closing wall for said recess, and means co-operating with the front wall of said water container for retaining the latter in said recess or well. 35

5. In a cooler of the character described, in combination, an ice container provided with a recess or well open at its front, a water container insertable into and removable from said recess or well through the open front thereof, and having its front wall provided with angle slots, and devices attached to the ice container and co-operating with said angle slots to permit the 40 water container to be inserted into and removed from said recess or well and co-operating with said front wall to retain the water container in said ice container. 45

6. In a cooler of the character described, 50 in combination, an ice container having a main compartment and side compartments extended from said main compartment and forming between them a recess or well open at its front, a water container insertable 55 into and removable from said recess or well through the open front thereof, and having its front wall forming the closing wall for said recess, and means for retaining the water container in said recess or well. 60

In testimony whereof, I have signed my name to this specification.

HERBERT J. WILLMOTT.
